UNITED STATES PATENT OFFICE.

FREDERICK N. ROSS, OF DETROIT, MICHIGAN, ASSIGNOR TO SATTLEY COMPANY, OF DETROIT, MICHIGAN, A CORPORATION OF MICHIGAN.

COIN-COUNTING MACHINE.

Application filed March 26, 1923. Serial No. 627,718.

To all whom it may concern:

Be it known that I, FREDERICK N. Ross, a citizen of the United States of America, residing at Detroit, in the county of Wayne and State of Michigan, have invented certain new and useful Improvements in Coin-Counting Machines, of which the following is a specification, reference being had thereto to the accompanying drawings.

10 The invention relates to coin counting machines of the type in which the coins are placed upon a revolving disk from which they are discharged tangentially through a counting device. The primary object of the invention is to obtain a simple construction of mechanism for counting various denominations of coins in predetermined units. Another object is to provide improved means for collecting and sealing the coins in suitable packages, while a still further object is to arrange the controlling mechanism of the machine in such relationship with the packaging device that successive units may be counted and packaged almost continuously, 25 thereby obtaining a large output.

These and other objects are attained by certain novel features of construction and arrangement of parts which are hereinafter fully set forth.

30 In the drawings:—

Figure 1 is a perspective view of the machine;

Figure 2 is a bottom plan view thereof;

Figure 3 is a transverse section on the line 3—3 of Figure 2;

Figure 4 is a transverse section on the line 4—4 of Figure 2;

Figure 5 is a longitudinal section on the line 5—5 of Figure 2;

40 Figure 6 is a fragmentary top plan view with the segment 37 removed;

Figure 7 is a bottom plan view of the segment 37;

Figure 8 is a transverse section on the line 8—8 of Figure 7;

Figure 9 is an elevation of the sacking tube.

In general construction, the machine comprises a table 1 supported on legs 2 and having mounted thereon a receptacle 3 containing a revoluble disk 4 forming the bottom thereof. The disk 4 is mounted upon a vertical shaft 5 journaled in bearings 6 in the table 1 and is driven by a friction disk 7 engaging the underside of the disk through

a slot 8 in the table. The disk 7 is mounted upon a shaft 9 journaled in hangers 10 and 11 and is driven by an electric motor 12 by means of a belt drive 13. In order to regulate the friction between the disks 7 and 4, 60 the rear bearing of the shaft 9 is pivoted at 14 in the rear hanger 10, while the front bearing is provided with a transverse pin 15 engaging vertical slots 16 in the front hanger 11. A tensioning screw 17 threadedly engages the hanger 11 and regulates the pressure of a coiled spring 18 interposed between the screw and the bearing.

The motor shaft 19 is extended to a bearing 20 supported at the front of the machine 70 by a bracket 21 and the shaft is provided with the coupling 22 whose function will hereinafter be explained. A yoke 23 is pivoted on the underside of the table 1 and contains at its free end a shaft 24 on which is 75 mounted a friction disk 25 engaging the revolving disk 4 through a slot 26 in the table. Pivoted upon the shaft 24 is a second yoke 27 containing at its free end a coin propelling wheel 28 which is driven from the friction disk 25 by a belt 29. The friction between the disks 25 and 4 is regulated by means of a tensioning screw 30 and the tension upon the coin propelling disk 28 is correspondingly regulated by means of the 80 tensioning screw 31.

The receptacle 3 is provided with an upstanding peripheral flange 32 having a portion 33 adjacent to the revolving disk 4 inwardly inclined to avoid stacking the coins 90 when thrown outward by the centrifugal action of the disk. 34 is a finger which projects inwardly from the peripheral wall of the receptacle adjacent to the discharge opening 35. In order to count coins of a 95 certain denomination, it is necessary to have the distance between the projecting finger 34 and the peripheral wall adjacent to the discharge opening conform to an exact dimension corresponding to the size of the 100 coin to be counted and it is usual to provide some sort of adjusting mechanism for regulating this distance and also the thickness of the discharge opening. In this machine, however, I have done away with the adjusting mechanisms and obtained the required dimensions for a certain coin by means of exchangeable templets 36. To accomplish this purpose a segment 37 of the peripheral flange 32 is removable and is ordinarily held 110

in place by means of the dowel pins 38. Secured to the bottom of the removable segment is a flat guide 39 whose inner edge 40 forms a continuation of the inner edge 41 of the finger 34 and serves to guide the excess coins away from the discharge opening. This guide is made complementary to the projecting finger 34 and forms also a cover for the discharge opening 35 in which the 10 coin propelling wheel 28 revolves.

The templet 36 is provided with apertures 42 and may be laid upon the table 1 and held in position by the dowel pins 38. The templet is the exact thickness of the 15 coin to be counted, thereby forming a space 43 between the revolving disk 4 and the flat guide 39 through which coins may pass to the discharge opening. The inner edge 44 of the templet 36 forms a guide for the 20 coins and at the discharge opening is located the proper distance from the projecting finger 34 to allow only one coin to pass at a time. The templet is provided with an arcuate surface 45 which bears against 25 the dowel pin 46 to accurately position the templet with respect to the projecting finger 34.

For each different type of coin to be counted there is a different templet having 30 a thickness corresponding to the thickness of the coin and an inner edge 44 of such a contour as to allow only one coin at a time to pass through the discharge opening.

35 As the coins reach the discharge opening they engage with the coin propelling disk 28 which is preferably made of rubber or other resilient material and are forced by a star wheel 47, which projects into the 40 path of the coins and is mounted upon a vertical shaft 48 journaled in the table of the machine. A suitable coin counter 49 is connected to the shaft by means of bevel gears 50 and the shaft is also provided with 45 a knurled knob 51 for adjusting the position of the star wheel by hand. When no coins are passing through the discharge opening, the coin propelling wheel 28 would ordinarily rub against the under surface of 50 the guide plate 39 and to prevent undue wear upon the disk, I have provided a slot 52 in the guide plate opposite the disk in which is arranged a transverse roller 53, the periphery of which is spaced slightly 55 from the plane of the surface so that the coins passing through the discharge opening will avoid contact therewith but allowing the propelling disk to roll in engagement therewith when no coins are passing through. The guide plate 39 is also provided 60 with the segmental recess 54 forming a housing for the portion of the star wheel projecting into the discharge passage-way.

65 It is desirable to limit the count of the

discharged coins to some predetermined number corresponding to the number of coins to be placed in a single wrapper or when the coins are to be placed in a bag to some larger number corresponding to the 70 capacity thereof. For accomplishing this purpose, I have provided a stop mechanism, which may be set to correspond with a plurality of different limits, for use with different denominations of coins. A pinion 55 is 75 secured to the shaft 48 upon the underside of the table 1 and is arranged to mesh with a plurality of gears 56, 57, 58. These gears are of different diameters but are eccentrically mounted upon a common shaft 59 in 80 such a manner that each gear is in mesh with the pinion 55 and, therefore, they are independently rotated at different angular velocities. As shown in the drawings, the mechanism is adapted to count in units of 85 20, 40, 50 or 500 and to do this, the smallest gear 56 is provided with eighty-eight teeth, the intermediate gear with one hundred teeth and the largest gear with one hundred and ten teeth. A lever 60 is swivelled to the underside of the table 1 and is provided at its free end with a trigger lever 61, one arm of which extends in front of the machine and the other arm of which carries a series of 90 dogs 62, 63, 64. These dogs are of different length and are spaced apart transversely of the trigger. A stop 65 prevents the relative movement of the trigger upon the lever 60 in one direction while the spring 66 yieldingly allows a pivotal movement in the 95 100 opposite direction. 67 is a main spring yieldingly holding the lever 60 adjacent to the gears and causing the dogs to engage upon the flat surface thereof. 68 is a trigger plate arranged in the front of the machine 105 having a series of notches 69, 70, 71, 72 corresponding to the different counts of the machine and in which the trigger is adapted to engage. The arrangement is such that when it is desired to count 20 coins at a time, the trigger is engaged with the notch 69 and in this position, the longest dog 62 bears on the surface of the gear 56. This surface is provided with diametrically opposite notches 73 with which the dog engages, thereby preventing the rotation of the star wheel 47. To release the mechanism to count another series of 20 coins, the trigger arm is manually tripped against the tension of the 110 spring 66, thereby allowing the star wheel 115 to be actuated by the coins from the revolving disk 4. To obtain a count of 40, the trigger arm is placed in the notch 70, this position allowing the dog 62 to engage the same gear wheel 56 but further toward the 120 periphery. At this point of the periphery, the wheel is provided with only a single notch so that the notch engages the dog only once in each revolution. Similarly, to obtain 125 a count of 50, the trigger is placed in the 130

notch 71 and in this position, the dog 62 bears on the surface of the large gear 58 which is provided with a single notch and the ratios of the gears are such that one revolution of the large gear wheel corresponds to a count of 50 coins. To obtain a count of 500, the trigger is placed in the last notch 72 and in this position, the dog 62 no longer engages with any of the gear wheels but the dogs 63 and 64 respectively bear upon the gear wheels 57 and 58. In this position, it will be apparent that the dogs will only stop the rotation of the gears when the notches in both of the gears 57 and 58 register with the dogs simultaneously and since the angular movement of the gear 57 is ten times that of the gear 58, it requires ten revolutions of the larger gear to bring the two notches into simultaneous engagement with the corresponding dogs. In this manner a count of 500 is obtained.

It will be evident from the foregoing discussion that, when changing from one count to another, the mechanism will not always function properly for the first series of coins discharged but to compensate for this, the instrument may be set by means of the knurled knob 51 which actuates the star wheel 47 until the proper dog engages the corresponding notch for the particular count which it is desired to obtain.

When it is desired to use the machine for packaging the coins in a wrapper, a packaging tube 74 is secured to the machine opposite the discharge opening. This tube has an internal diameter corresponding to the diameter of the denomination of coins which are being counted and is provided at the bottom with a flaring mouth 75 into which a coin wrapper may be inserted. It is also desirable to provide a means for closing the end of the coin wrapper and I have, therefore, provided a crimping mechanism 76 which is arranged upon a laterally extending bracket 77 from the tube 74 and provided with a revoluble cone shaped member 78 having a coupling 79 adapted to engage the pin 22 on the motor shaft 19. The packaging tube 74 is provided with the flat surface 80 for engaging the corresponding surface 81 upon the edge of the table and is held in position by ears 82 engaging lugs 83 on the table and positively secured thereto by a swivel bracket 84 and set screw 85. When it is desired to package coins of a different denomination, the packaging tube is replaced by a similar tube having an inner diameter corresponding to the coin to be packaged and having also a crimping mechanism adapted to close the wrapper used for this particular coin. Each crimping mechanism comprises the cone shaped cylindrical member 78 which contains the annular groove 86 of the proper diameter to receive the edge of the coin wrapper. Extending radially

within the groove are the rollers 87 which are also grooved to turn the edge of the wrapper inward and form a sealing return bend.

When it is desired to count coins in bulk, there is provided a sacking tube 88 which may be secured to the table in the same manner as the packaging tube but which is of large enough internal diameter to take the largest coin which the machine is adapted to count. The sacking tube is provided with a grip 89 consisting of two spring arms 90 between which the edge of the bag or sack may be inserted during the counting. There is also provided a bracket 91 which may be engaged with the legs 2 when the machine is placed near the edge of a supporting table, the bracket extending downward and forming a shelf 92 on which the bag may be rested while being filled with coins.

There is also provided a hopper 93 which is adapted to be placed upon the receptacle 3 into which the bulk coins may be deposited and fed upon the revolving disk. A switch 94 is located on the forward end of the table and adapted to start and stop the motor 12.

In the operation of the machine, the revolving disk 4 is set in motion by operating the switch 94 and the coins are forced outward by centrifugal action against the inclined portion 33 of the peripheral flange of the receptacle. A templet 36 of the proper size to be used with a certain denomination of coins having been previously placed in position and the corresponding packaging tube 74 having been secured in place, the operator places a coin wrapper in the lower end of the packaging and trips the trigger lever 61. This allows a predetermined number of coins to be filled into the wrapper whereupon, the operator removes the filled wrapper with one hand and inserts the same in the crimping mechanism 76, at the same time inserting a new wrapper in the packaging tube with the other hand and operating the trip with the same hand that is grasping the filled wrapper. It will be seen that by having these various mechanisms arranged upon the same side of the machine it is possible to count and package the coins in the minimum amount of time.

When it is desired to count coins of a different denomination it is only necessary to remove the segment 37 by loosening the retaining swivel bracket 95 and replace the templet with one corresponding to the next denomination to be counted. A corresponding packaging tube may then be placed in the swivel bracket 84 which at the same time connects a crimping mechanism of corresponding size to the motor shaft 19.

What I claim as my invention is:

1. In a coin counting machine, the combination with a revoluble disk, of a recep-

tacle surrounding said disk provided with an opening for the discharge of coins therethrough, and exchangeable guides for varying the size of said discharge opening corresponding to coins of different denominations.

2. In a coin counting machine, the combination with a revolute disk, of a receptacle surrounding said disk provided with an opening for the discharge of coins therethrough, a member forming a guide channel for the discharged coins, and exchangeable guides cooperating with said member to vary the size of said channel corresponding to coins of different denominations.

3. In a coin counting mechanism, the combination with a revolute disk, of a receptacle surrounding said disk, a table in the plane of said disk, a member having a guide surface parallel to said table, and exchangeable guides spacing said guide member from said table to form a channel corresponding to coins of different denominations, said exchangeable guides being of different contour corresponding to the width of said coins.

4. In a coin counting mechanism, the combination with a revolute disk, of a receptacle surrounding said disk having a discharge opening for the passage of coins, a finger projecting from one end of said opening, and exchangeable guides spaced from said finger to vary the width of the discharge channel corresponding to the diameter of coins of different denominations.

5. In a coin counting mechanism, the combination with a revolute disk, of a circular receptacle surrounding the periphery of said disk, a finger projecting from said receptacle and extending over said disk forming one side of a discharge channel, exchangeable members forming the opposite side of said discharge channel, said members being of different widths and contours to vary the width of said channel corresponding to coins of different denominations, and a cover for said channel spaced from said disk by said exchangeable members to vary the depth of said channel corresponding to the thickness of said coins.

6. In a coin counting machine, the combination with a revolute disk, of a receptacle surrounding the periphery of said disk having an opening forming a channel for the discharge of coins therethrough, a star wheel in said channel actuated by the discharge coins, and exchangeable guides for varying the size of said channel adjacent to said star wheel corresponding to coins of different denominations.

7. In a coin counting mechanism, the combination with a revolute disk, of a receptacle surrounding said disk having an opening forming a channel for the discharge of coins therethrough, a removable segment provided with a top guide surface for said

channel, a finger projecting from said receptacle and forming one side of a discharge channel, and exchangeable guides forming the opposite side of said channel and arranged beneath said removable segment to space the same from said disk thereby forming a channel corresponding to coins of different denominations.

8. In a coin counting mechanism, the combination with a star wheel actuated by the passage of the coins, of a series of revolute members provided with stops and driven by said star wheel at different speeds, and a cooperating stop member adjustably arranged to selectively engage the stops on the respective revolute members to variably limit the count of said star wheel.

9. In a coin counting machine, the combination with a star wheel actuated by the passage of the coins, of a series of members adapted to be rotated by said star wheel at different speeds, said members being provided with stops, a pair of cooperating stop members, each arranged in the path of a stop on a revolute member, means for yieldingly moving said cooperating stops into engagement with the stops on said revolute members only when the latter are in predetermined relative position and means for adjusting the position of one of said cooperating stop members to avoid the path of said revolving stop.

10. In a coin counting mechanism, the combination with a star wheel actuated by the passage of the coins, of a series of revolute members adapted to be driven by said star wheel at different speeds, a spring pressed member having a pair of dogs adapted to simultaneously bear against two of said revolute members, cooperating stops upon said revolute members engageable with said dogs only when in predetermined relation to each other and means for adjusting said spring pressed member to withdraw one of said dogs from engagement with the cooperating revolute member.

11. In a coin counting machine, the combination with a star wheel actuated by the passage of the coins, of a series of revolute members adapted to be driven by said star wheel at different speeds, a spring pressed member having a plurality of dogs extending therefrom, said member being adjustable in a plurality of positions to selectively cause one or more of said dogs to bear against one or more of said revolute members, and said revolute members being provided with recesses for receiving said dogs to limit the actuation of said star wheel to a plurality of predetermined counts.

12. In a coin counting machine, the combination with a star wheel actuated by the passage of the coins, of a series of revolute members provided with stops and geared to said star wheel to rotate at different speeds,

a cooperating stop member adjustably arranged to selectively engage the stops on the respective revoluble members to variably limit the count of said star wheel, and means 5 for tripping said stop member to release engagement of said stops for obtaining successive counts.

13. In a coin counting machine, the combination with a star wheel actuated by the 10 passage of the coins, of a pinion secured to said star wheel, a plurality of gears of different diameters eccentrically mounted with respect to each other and driven by said pinion, each of said gears being provided 15 with an annular bearing surface having a notch therein, a stop having a plurality of dogs, means for adjusting said stop to a plurality of different positions to vary the count of the coins, one of said positions being such 20 that two of said dogs simultaneously engage two of said annular surfaces and enter the corresponding notches only when the latter are in predetermined relative position.

14. In a coin counting machine, the combination with a star wheel actuated by the 25 passage of the coins, of a pinion revoluble therewith, a plurality of gears of different diameters eccentrically mounted with respect to each other and driven by said pinion, each 30 of said gears being provided with an annular bearing surface having a notch therein, a

lever, a second lever, a plurality of dogs on said second lever, means for adjusting said dogs substantially radially of said gears to a plurality of different positions for 35 varying the count of the coins, a spring connected to said first mentioned lever causing a yielding engagement of a dog, and a bearing surface in each of said positions, whereby it enters the corresponding recess 40 to stop the count.

15. In a coin counting machine, the combination with a table, and a revoluble disk mounted thereon, of a receptacle surrounding said disk provided with an opening for 45 the discharge of coins therethrough, a star wheel actuated by the passage of the coins to count the same, a motor for driving said revoluble disk, a coupling located at the discharge end of the machine and driven by 50 said motor, exchangeable packaging and sealing units adapted to be removably secured to said table in alignment with said discharge opening, each of said units comprising a tubular channel corresponding to 55 a certain denomination of coins and outwardly flaring to receive a corresponding coin wrapper, and a revoluble crimping mechanism engageable with said coupling.

In testimony whereof I affix my signature.

FREDERICK N. ROSS.
